UNITED STATES PATENT OFFICE.

ISAAC LEVY, OF BROOKLYN, NEW YORK.

DESIGN FOR A CEILING PLATE.

61,097.

Specification for Design. Patented June 20, 1922.

Application filed September 20, 1921. Serial No. 502,073. Term of patent 3½ years.

To all whom it may concern:

Be it known that I, ISAAC LEVY, a citizen of the United States, residing at Brooklyn, in the county of Kings and State of New York, have invented a new, original, and ornamental Design for a Ceiling Plate, of which the following is a specification, reference being had to the accompanying drawing, forming part thereof.

In the drawings:—

Figure 1 is a side view of the ceiling plate.

Figure 2 is a bottom plan view thereof.

I claim:—

The ornamental design for a ceiling plate as shown.

ISAAC LEVY.
